United States Patent Office

Des. 205,781
Patented Sept. 20, 1966

205,781

BEVERAGE SERVER OR THE LIKE

Howard C. Valle and Samuel E. Hatchett, San Diego, and Raymond E. Gust, Spring Valley, Calif., assignors to Courtesy Products Corporation, San Diego, Calif.

Filed Oct. 18, 1965, Ser. No. 87,556

Term of patent 14 years

(Cl. D44—21)

FIG. 1

FIG. 6

FIG. 3

FIGURE 1 is a perspective view of a beverage server or the like showing our new design:

We claim:

The ornamental design for a beverage server or the like, substantially as shown.
